(57) **CLAIM**

The ornamental design for a lipstick case, as shown and described.

DESCRIPTION

FIG. 1 is a top and side perspective view of our new design for a lipstick case, the opposite side being a mirror image thereof; FIG. 2 is a side elevational view of the lipstick case shown in FIG. 1; and,

FIG. 3 is a top plan view of the lipstick case shown in FIG. 1, the bottom plan view being identical thereto.
